UNITED STATES PATENT OFFICE

GIULIO CICCONI, OF SMOCK, PENNSYLVANIA, ASSIGNOR OF ONE-HALF TO GEORGE A. ANDRESKOVICH, OF MONESSEN, PENNSYLVANIA.

CLOTHES HANGER

Application filed October 9, 1930. Serial No. 497,576.

This invention relates to improvements in hangers for articles of clothing and relates particularly to hangers of the character known as coat hangers.

- 5 The primary object of the present invention is to provide a coat hanger with means whereby an article hung across the horizontal bar portion thereof may be securely held against sliding movement on this bar, so that 10 in the delivery of clothing after the same have been purchased or after they have been cleaned and pressed, an article suspended across the bar of the hanger will not slip to one side and become wrinkled.
- 15 Another object of the invention is to provide a device of the above described character which may be easily and inexpensively combined with a coat hanger, and which may be easily and quickly manipulated to secure 20 or release an article suspended on the hanger.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

25 Figure 1 shows a hanger constructed in accordance with my invention.

Figure 2 is a sectional view taken on the line 2-2 of Figure 1.

Referring more particularly to the drawing wherein like numerals of reference indicate corresponding parts throughout the several views, the numeral 1 indicates generally a stiff wire coat hanger of the usual design having a horizontal bar portion 2 and inclined side bars 3, which converge and are joined by twisting, as indicated at 4, at the point above the central part of the bar 2, one of the side bars 3 being extended and formed to provide a hook 5 by means of which the hanger may be hung up.

In association with a hanger of the above described character I provide an eye 6, preferably formed of heavy wire of the same gauge as that from which the hanger is constructed. This eye is provided with relatively long end portions which are twisted together as indicated at 7 so that the eye will be completely closed, and each is then twisted about one of the inclined shoulder bars 3 of the hanger in the manner indicated by the numeral 8 so that the eye or ring 6 will be located between the bars 3 and the bar 2 directly beneath the hook of the hanger.

Suspended from the eye 6 is an elongated substantially U-shaped resilient clasp, which is indicated as a whole by the numeral 9. The side members or legs 10 of the clasp 9, which is formed of a single piece of material as shown, are joined by the narrow bight portion 11 which engages the eye 6, the ends of the legs 10 being disposed at opposite sides of the bar 2 as shown in Figure 2. Adjacent its free end each leg 10 is bent inwardly as indicated at 12 so that an article may be gripped therebetween, as illustrated, beneath the bar 2 without bringing the legs into contact with the bar. Surrounding the clasp 9 is a ring 13 which, when slipped downwardly upon the divergent legs 10, will cause the ends thereof to be drawn together so as to grip an article such as is indicated by the numeral 14, in the manner shown.

From the foregoing description it will be readily seen that when an article of clothing such, for example, as a pair of trousers is suspended across the bar 2 the clasp 9 may be employed for holding the article against movement on the bar so that when the article is being delivered after being pressed it will not slip over to one side of the hanger and become wrinkled.

Having thus described my invention, what I claim is:—

1. The combination with a coat hanger having a horizontal bar portion and side bars disposed in convergent relation and joined above the horizontal bar, of a ring member disposed beneath the points of convergence of the side bars, said ring being formed with end portions each of which is twisted about

an adjacent side bar, a resilient clasp suspended from said ring and having a pair of spaced leg members arranged with said horizontal bar disposed therebetween, and means for drawing said leg members together to secure an article suspended on the horizontal bar.

2. The combination with a coat hanger having a horizontal bar portion and side bars disposed in convergent relation and joined above the horizontal bar, of a ring member disposed beneath the points of convergence of the side bars, said ring being formed with end portions each of which is twisted about an adjacent side bar, a resilient clasp member of elongated, substantially U-shaped configuration, having said ring engaged therewith between side members thereof and having said side members disposed with the horizontal bar therebetween, the said side members of the clasp being inset adjacent their free ends and beneath the horizontal bar, and means for forcing the side members of said clasp together to secure therebetween an article suspended from the horizontal bar.

3. A clothes hanger comprising a wire body bent to form a straight bar and a pair of shoulder bars extending from the ends of the straight bar and converging at a point above the same, said shoulder bars at their point of convergence being twisted together and one thereof being extended to form a hook, a ring member formed of wire and having ends twisted together, said twisted portion of the ends being disposed beneath and in alignment with the twisted ends of said shoulder portions to suspend the ring above the straight bar and the ends of said ring being extended in opposite directions and each twisted about a shoulder, and a clamp member carried by and depending from said ring and engaging over said straight bar to secure a garment thereto.

In testimony whereof I hereunto affix my
signature.

GUILIO CICCONI.
